UNITED STATES PATENT OFFICE.

WALTER A. FELLOWES, OF CHICAGO, ILLINOIS.

CLOSURE FASTENER FOR BOXES.

Application filed December 22, 1922. Serial No. 608,523.

To all whom it may concern:

Be it known that I, WALTER A. FELLOWES, a citizen of the United States, residing at Chicago, in the county of Cook and State of 5 Illinois, have invented new and useful Improvements in Closure Fasteners for Boxes, of which the following is a specification.

My invention relates to improvements in closure fasteners for boxes and has for its 10 primary object the provision of a novel and improved fastening means which obviates the necessity of the use of string or tape.

A further object of the invention is to provide a fastening expedient which may be 15 quickly applied to boxes of various constructions and materials, such expedient being very simple, inexpensive of manufacture, and highly efficient in operation.

With the above and other objects in view, 20 as will become more apparent as the description proceeds, the invention comprises certain novel features of construction and arrangement to be hereinafter described and claimed, and in order that the same may be 25 better understood, reference is had to the accompanying drawing forming a part of this specification.

In the drawing,

Figure 1 is a perspective view of a box 30 illustrating the application of my improved closure fastener thereto;

Fig. 2 is a cross-section through the box and one of the fasteners, and

Fig. 3 is a detail perspective view of one 35 of the fastening elements removed.

Referring specifically to the drawing illustrating the preferred embodiment of my invention, like reference characters designating like parts throughout the several 40 views, numeral 5 denotes a box of cardboard, metal or any other suitable material, which in this instance is formed of cardboard having a pair of longitudinal flaps 6 and end flaps 7. In Figure 1 of the drawing, 45 the box is shown closed, the two longitudinal flaps being folded down over the end flaps 7.

Coming now to the closure fastening means which is the subject matter of my invention, it will be noted that the box is

provided with pairs of opposed studs 8 extending transversely through the side walls of the box from the outside thereof, these studs being provided with enlarged bases 8^a resting against the inside of the box wall. 55 The forward portions of the studs 8 extend through the walls of the box and are received in apertures 11 in the opposed laterally bent ends 10 of a spring metal fastening clip 9 which is fitted down snugly 60 against the closed flaps 6.

From the foregoing description read in connection with the accompanying drawing, the application of my invention will be readily understood. In applying the clips 65 9 it is only necessary to press them down upon the top of the box and clip the studs 8 in the apertures 11. This construction obviates the use of string and the consequent loss of time in tying the same. Also when 70 string is used to tie boxes there is a temptation to carry the same thereby, which frequently results in its breaking and the spilling of the contents of the box.

Various changes in the specific details and 75 arrangement of the parts may be made within the spirit of the invention, the scope of which is defined by the following claim.

Having thus described my invention, what I claim as new and desire to secure by 80 Letters Patent is:

The combination with a box having a closure, of a U-shaped fastener formed from a single length of spring metal and having a bight portion extending across and flatly 85 contacting with said closure to hold the same in position, said U-shaped body having sides flatly contacting with the sides of said box and having their terminal portions arranged between the upper and lower sides 90 of the box and formed with apertures, and pins carried by the sides of the box and adapted to be received in said apertures whereby to hold the U-shaped body securely 95 in position, said side of the U-shaped body being freely removable from said pins whereby the U-shaped body may be quickly detached.

In testimony whereof I affix my signature.

WALTER A. FELLOWES.
